(57) **CLAIM**

We claim the ornamental design for a movement measurement device housing, as shown and described.

DESCRIPTION

FIG. 1 is a front isometric view of a first embodiment of a movement measurement device housing.

FIG. 2 is a rear isometric view of the movement measurement device housing of FIG. 1.

FIG. 3 is a front elevation view of the movement measurement device housing of FIG. 1.

FIG. 4 is a rear elevation view of the movement measurement device housing of FIG. 1.

FIG. 5 is a right side elevation view of the movement measurement device housing of FIG. 1.

FIG. 6 is a left side elevation view of the movement measurement device housing of FIG. 1.

FIG. 7 is a top plan view of the movement measurement device housing of FIG. 1.

FIG. 8 is a bottom plan view of the movement measurement device housing of FIG. 1.

FIG. 9 is a front isometric view of a second embodiment of a movement measurement device housing.

FIG. 10 is a rear isometric view of the movement measurement device housing of FIG. 9.

FIG. 11 is a front elevation view of the movement measurement device housing of FIG. 9.

FIG. 12 is a rear elevation view of the movement measurement device housing of FIG. 9.

FIG. 13 is a right side elevation view of the movement measurement device housing of FIG. 9.

FIG. 14 is a left side elevation view of the movement measurement device housing of FIG. 9.

FIG. 15 is a top plan view of the movement measurement device housing of FIG. 9; and,

FIG. 16 is a bottom plan view of the movement measurement device housing of FIG. 9.

The dashed lines illustrate portions of the movement measurement device housing that form no part of the claimed design.
